United States Patent Office

Des. 186,063
Patented Sept. 1, 1959

186,063

PLASTIC WALL COVERING OR SIMILAR ARTICLE

Harry P. Schaefer, Cisco, Tex., assignor of fifty percent to J. H. Reynolds, Cisco, Tex.

Application December 9, 1957, Serial No. 48,835

Term of patent 7 years

(Cl. D87—3)

Fig. 1

Figure 1 is a plan view showing my design for a plastic wall covering or similar article; and

I claim:

The ornamental design for a plastic wall covering or similar article, as shown.
